UNITED STATES PATENT OFFICE.

FREDRIC EDHOLM, OF ESKILSTUNA, SWEDEN.

REGULATING DEVICE FOR INTERNAL-COMBUSTION ENGINES.

1,319,857.

Specification of Letters Patent.

Patented Oct. 28, 1919.

Application filed March 28, 1919. Serial No. 285,940.

To all whom it may concern:

Be it known that I, FREDRIC EDHOLM, a citizen of the Kingdom of Sweden, residing at Eskilstuna, Sweden, have invented new 5 and useful Improvements in Regulating Devices for Internal-Combustion Engines, of which the following is a specification.

This invention relates to a regulating device for internal combustion engines having 10 a fuel supply pump, the object of the invention being to provide a regulating device for such engines in which one stroke of the fuel supply pump is effected by means of a cam disk attached to a power shaft while 15 the opposite stroke of the pump is effected by a spring and limited by a conical sleeve mounted on said shaft and adjustable along the same under the control of a governor in order that the governor may be subjected 20 to load arising from the pump during part of one stroke of the pump only.

In the accompanying drawing forming part of this specification, Figure 1 shows a sectional elevation of one embodiment of 25 the invention. Fig. 2 shows certain parts of this embodiment in top plan view. Fig. 3 shows a sectional elevation of another embodiment of the invention.

In the embodiment shown in Fig. 1, 1 indicates a power shaft and 2 a stationary casing through which the shaft 1 extends. Mounted in said casing to move in a direction at right angles to the shaft 1 is a slide 3 recessed in its outer end to receive the plunger 30 4 of a fuel supply pump 5, said plunger being maintained in contact with the bottom of said recess by means of a spring 6 confined between a shoulder 20 formed on the casing 2 and a collar 21 on the plunger 4. Mounted 35 in the slide 3 is a bolt 7 which forms the journal shaft of a cylindrical roller 8 situated over against a cam disk 9, attached to the shaft 1 the form of which will be seen from Fig. 2. The slide 3 further carries a journal pin 10 for a conical roller 11, situated over against a correspondingly conical sleeve 12 the base of which is directed oppositely to that of the roller 11. The sleeve 12 is mounted on the shaft 1 to be displaced 40 longitudinally thereon. A ring 120 loosely mounted in an annular groove in the sleeve 12 is connected to a rock lever 13 adapted to be connected with a governor, not shown. Mounted on the casing 2 is a lever 15 by 45 means of which the slide 3 may be operated manually.

Assuming the shaft 1 rotates in the direction of the arrow shown in Fig. 2, the device above described operates as follows: With the position of the roller 8 shown in 50 Fig. 2, the cam disk 9 will first touch the roller 8 in the point *a*, whereupon the cam disk displaces the roller 8 and thus also the slide 3 with the pump plunger 4 outwardly in opposition to the spring 6 until the point *b* touches the roller 8. The said displacement effects the pressure stroke of the plunger. While the portion *b c d* of the circumference of the disk 9 concentric to the shaft 1 bears against the roller 8 the plunger 50 4 will be maintained in its extreme inner position relatively to the pump cylinder 5 and will be successively returned to its outer end position by means of the spring 6 after the point *d* has come into contact with the roller 55 8. Said movement, viz. the suction stroke of the plunger, proceeds until the roller 11 encounters the conical sleeve 12 which is maintained in a position corresponding to the actual load of the engine by means of 60 the governor. While the roller 11 engages with the sleeve 12 no change takes place in the movement of the plunger unless a change in the load of the engine effects an adjustment of the sleeve. When the roller 8 is 65 again brought into contact with the cam disk 9 at or near the point *a*, the roller 11 is removed from the sleeve 12 by the movement of the slide 3. The engagement between the roller 11 and the sleeve 12 will 70 thus exist during only a small part of each revolution of the shaft 1 the sleeve 12 being freely adjustable by means of the governor during the rest of each revolution.

As the counteracting effect of the device 75 on the operation of the governor depends on the axial pressure component of the roller 11 on the sleeve 12, it is obvious that by using a small pitch for the roller 11 and the sleeve 12 and by using a spring 6 the 80 pressure of which is not greater than is necessary to overcome the suction resistance of the pump during the period the circumferential portion *d-a* of the cam disk is in engagement with the roller 8, the said 85 counteracting effect on the governor may be reduced to a very small value.

The embodiment shown in Fig. 3 differs from that above described only therein that the conical roller 11 is mounted in a separate slide 14 which is caused to bring the roller 11 into engagement with the sleeve 90

12 by the action of the slide 3, whereas the said slide 14 does not move with the slide 3 in the direction from the shaft 1.

I claim—

5 1. A regulating device for internal combustion engines, comprising a fuel supply pump, having a reciprocating plunger, a power shaft, a cam disk on said shaft, a conical sleeve slidably mounted on said 10 shaft, a slide for operating said pump plunger in one direction, a spring for moving the plunger in the opposite direction, a cylindrical roller on said slide for engagement with said cam disk and a conical 15 roller on said slide for engagement with said conical sleeve.

2. Regulating device for internal combustion engines, comprising a fuel supply pump having a reciprocating pump plunger, 20 a power shaft, a cam disk on said shaft, a conical sleeve on said shaft, means for adjusting said sleeve along the shaft according to the load of the engine, a slide for oper-

ating said pump plunger in one direction, a spring for moving the plunger in the 25 opposite direction, a cylindrical roller on said slide for engagement with said cam disk, and a conical roller on said slide for engagement with said conical sleeve.

3. Regulating device for internal combustion engines, comprising a fuel supply pump, having a reciprocating plunger, a power shaft, a cam disk on said shaft, a conical sleeve slidably mounted on said shaft, a slide for operating said plunger in one direction, a spring for moving the plunger in the opposite direction, a cylindrical roller on said slide for engagement with the cam disk, a conical roller on said slide for engagement with said conical sleeve, a housing surrounding said elements, and a 35 40 guide-way formed in said housing for the said slide.

In testimony whereof I have signed my name.

FREDRIC EDHOLM.
